METHODS FOR TREATING BITUMINOUS SHALES

Jean Léon Maurice Fréjacques, Paris, France, assignor to Compagnie de Produits Chimiques et Électrométallurgiques Alais, Froges et Camargue, Paris, France, a corporation of France

Application April 24, 1945, Serial No. 590,106
In France February 13, 1942

Section 1, Public Law 690, August 8, 1946
Patent expires February 13, 1962

4 Claims. (Cl. 196—78)

1

Gasoline and lubricating oils obtained from raw oils produced in the distillation of bituminous schists generally contain a large amount of sulphur and a comparatively important proportion of unsaturated hydrocarbons which render refining somewhat difficult. When refining according to the conventional method, i. e. by washing with soda and with sulphuric acid, the treatment is accompanied by important losses, due both to dissolution and to polymerization. The lubricants which can be removed from the raw oil are produced with a low yield and are generally of poor grade.

The accompanying drawing is a diagrammatic representation of a flow sheet of the process.

The present invention has for its object a method for obtaining a high-grade sulphur-free lubricant, starting from bituminous schists. According to this method, the schists are distilled in the presence of oils of medium volatility produced during a preceding operation, after which the oil thus obtained is submitted to fractional distillation and the lighter fractions are treated with a catalyst of the Friedel and Craft type consisting of a suitable anhydrous halide of an at least trivalent element (for instance aluminium chloride). The oil thus produced is fractionated for collecting the lubricant.

In order that this production may be really of interest, it is necessary to start from crude distilled oils containing sufficiently important proportions of unsaturated hydrocarbons, say about 30 to 40% or even more. Such percentages of olefines can be obtained by providing for a suitable progress in the distillation of the schists undergoing treatment. To this end, it is necessary to use retorts adapted to be heated in a comparatively rapid manner, so as to bring the schist to 400-500° C. and it is also necessary to recycle inside the furnace those fractions of the raw oil which form neither gasoline nor lubricating oils. The distillation furnace should be arranged in a manner such that this reintroduction can be conveniently performed. This recycling can be effected at very different levels and it is even possible merely to impregnate with oils the lumps of schist which are to be distilled before introducing them inside the furnace.

The oils of medium volatility that are thus recycled are subjected to a series of distillations which transform them little by little into gasoline with high contents of unsaturated hydrocarbons.

Outwardly heated rotary furnaces are very suitable for such schist treating operations.

2

The temperature at which distillation of the oil resulting from the distillation of schist should be stopped for obtaining the fraction to be treated with aluminium chloride depends on the nature of the schists used and on the grade of oil which it is desired to obtain. Generally a temperature comprised between 200 and 250° C. is of advantage.

When the distillation is thus stopped, it is possible to remove through subsequent distillation, from the remaining oil, pitch, lubricating oils and oils of medium volatility. The lubricating oils may be refined through the usual methods and used as such, but their refining is difficult and it is often of advantage to treat them again in the schist-distilling furnace together with the oils of medium volatility. Pitch may also be redistilled inside the furnace, but it generally produces only little oil with large amounts of coke and of gasses and it is generally more advantageous to use it separately.

The light oils obtained from the distillation of the mixture of oils resulting from the distillation of schists may be submitted to a slight refining with soda or with sulphuric acid before they are treated with aluminium chloride. It is thus possible to reduce the proportion of aluminium chloride required. The latter is variable in accordance with the nature of the schist treated and should be equal as an average to 5 to 10% in weight of the olefines contained in the oil.

The viscosity and the different qualities of the oils obtained may be modified almost at will by a modification in the conditions of polymerization.

At normal room temperature or at even lower temperatures, say below 0° C., the viscosities obtained are very high. At higher temperatures, say 50-80° C., it is possible to obtain more fluid oils. It may also be of interest to begin the polymerization at low temperature and to prosecute it then at high temperature. All these conditions have obviously their influence also on the duration of the treatment which may be given out by way of indication as lasting a few hours at high temperature or a few days below freezing point. A good stirring is required throughout the period of treatment.

When the polymerization is at an end, the oil may be treated as disclosed hereinafter: the oil is allowed to rest or if required submitted to centrifugation for separating the aluminium chloride which is contained in the oil in the form of a double insoluble combination. The oil is then filtered with a little discolored earth or active carbon

or even simply charcoal. It is of interest that these filtration furthering means be suitably dried before use so as to avoid the action of moisture on aluminium chloride. After filtration, the oil is washed with soda and then distilled for collecting its different fractions. The fraction distilling below 180-215° C. forms a very stable fuel which is completely colorless and shows absolutely no tendency towards forming gums. It is sufficiently desulphurized to allow its use without danger in 10 motors.

The treatment may moreover end with a last sulphuric refining which may then be performed with very small losses.

The fractions passing above 200° C. under 20 mm. of mercury form the lubricating oils. They are of very slight color and generally show a high viscosity index; they may be treated in accordance with the ordinary methods for making different desired grades of lubricants.

The intermediary oils of medium volatility are mixed with the fractions left after the removal of the lighter fractions from the oil resulting directly from the distillation of the schists and the mixture is reintroduced into the furnace as explained hereinabove.

The gases passing out of the retorts after condensation of the oil resulting from the distillation of the schists contain still some very light gasoline and easily condensable gases; it is of interest to recover these and to polymerize them. The light gasoline thus recovered may be polymerized by means of aluminium chloride together with the other polymerizable fractions or else separately from said last mentioned fractions, which permits of obtaining different grades of oil.

The easily condensable gases which it is possible to recover for instance by means of a treatment with active carbon may be treated in different manners. It is possible merely to make them bubble through oil stirred with aluminium chloride, so that they undergo polymerization; the olefines they contain are absorbed and transformed into oil. It is also possible to treat the gases directly with solid aluminium chloride either at atmospheric pressure or under a higher pressure. Lastly it is also possible to polymerize them into gasoline in accordance with any known method and then to polymerize this gasoline by means of aluminium chloride as in the case of light gasoline.

I will now give examples of the method according to the present invention.

Example I.—The bituminous schist that is treated is a schist from the Aveyron yielding 4.5 per cent of oil in the Fischer retort.

This schist is impregnated with 50 kgs. per ton of oil to be recycled resulting from a prior operation. The whole is distilled in a rotary furnace of the externally heated type. The matter remains about 15 minutes in the furnace. The thickness of the layer of schist in the furnace is 80-99 mms. The temperature of this schist at the hottest point is 480°, which corresponds, on the outside of the furnace, to a temperature of the combustion gases of 800° C. on the side through which the mass of schist leaves the furnace and 540° on the opposite side. The furnace is swept with a stream of steam of 200 kgs. per ton of schist. At the outlet of the furnace, I collect, per ton of schist: 91 kgs. of oil of a density of 0.960, obtained by mere condensation, and 16 cubic meters of gas from which can be extracted, by cooling at -40° C., 5.3 kgs.

of light gasoline. The 91 kgs. of oil thus obtained are fractionated and yield:

	Kgs.
Gasoline passing below 215° C. under atmospheric pressure	13.6
Medium oil to be recycled passing below 170° C. under a pressure of 2 mm. of mercury	50.5
Raw lubricating oil passing from 170 to 305° C. under a pressure of 2 mm. of mercury	21.5
Residuary pitch	5.4

The 13.6 kgs. of gasoline thus obtained are mixed with the 5.3 kgs. of light gasoline obtained from the gas, thus giving a total of 18.9 kgs. of gasoline to be polymerized. This gasoline contains a total amount of 2.7 per cent of sulphur. It is treated with 1 kg. of anhydrous aluminium chloride. The mixture thus formed is kept for 15 eight hours at ordinary temperature, then gradually heated to 60° C. in three hours and kept at this temperature for three other hours. The mixture is treated with water slightly acidulated with hydrochloric acid so as to permit of separating aluminium chloride by decantation. The decanted oil is washed with a 1 per cent solution of soda and subjected to fractional distillation. This treatment yields 11.8 kgs. of gasoline passing below 215° C. under atmospheric pressure, 15 kgs. of medium oil to be recycled passing below 170° C. under a pressure of 2 mm. of mercury and 4.2 kgs. of residuary oil which is mixed with the 21.5 kgs. of raw lubricating oil precedingly obtained, making a total of 25.7 kgs. of raw lubricating oil 20 to be refined. The gasoline thus obtained contains only a total amount of 0.3 per cent of sulphur. It no longer contains corrosive sulphur. It is perfectly colorless, does not get yellow after a certain time and has no tendency to form gums. Its octane index is 72.

The raw lubricating oil can be refined through any known means. Treatment by selective solvents permits for instance of extracting therefrom from 10 to 13 kgs. of oil suitable for consumption and which may be fractionated so as to yield about 40 per cent of fluid oil of 2° Engler at 50° C., 40 per cent of oil of 2° Engler at 50° C. and 20 per cent of viscous oil of 21° Engler at 50° C., having a viscosity index of 55-60.

Example II.—The operation is conducted as above, but the first fractionating of the oil obtained from the treatment of schist in the furnace takes place at a temperature of 250° C. instead of 215° C. and the lubricating oil is not separated from the medium oil. The resulting products are:

	Kgs.
Light oil passing below 250° under atmospheric pressure	36.5
Medium oil to be recycled	50
Pitch	5.5

The 36.5 kgs. of light oil passing below 250° C. are treated with 1.2-2 kgs. of anhydrous aluminium chloride at ordinary temperature. During this time the gases flowing out from the schist furnace are caused to bubble through this mixture. These gases are subsequently cooled down to a temperature of -40° C. for extracting therefrom the gasoline that has been driven along. About 4 kgs. of light gasoline are thus collected. The mixture of oil and aluminium chloride is then brought to a temperature of 60° C. as in the above example. After separation of the aluminium chloride, the polymerized oil is fractionated,

yielding 7.5 kgs. of refined gasoline, 17.8 kgs. of medium oil and 13.5 kgs. of lubricating oil which can be refined with an excellent yield through a mere treatment with sulphuric acid followed with a filtration with discolouring earth. The medium oil that is obtained is very little coloured and very well refined. It can also be recycled but it is preferable to use it as such.

Of course, processes intermediate between those indicated in the two above examples can be utilized. For instance only a portion of the lubricating oils and a portion of the medium oils resulting from polymerization might be recycled.

Various modifications may be brought to this method without widening the scope of the present invention. For instance, it is often of interest to add to the aluminium chloride used a certain amount of powder of aluminium. It is also possible to use for instance zinc chloride, ferric chloride, boron fluoride, stannic chloride or a mixture of such catalysts.

What I claim is:

1. A method for producing a sulfur-free high grade lubricant from bituminous schists, which comprises initially distilling said schists in the presence of a recycle oil fraction of boiling range intermediate lubricating oil and gasoline and obtained from a prior fractional distillation operation, to produce a distillate oil, subjecting the distillate oil so produced to fractional distillation to obtain a lighter fraction and a heavier fraction, subjecting the lighter fraction to a polymerization treatment with a metal halide catalyst of the Friedel and Crafts type to produce a polymerization product, fractionating the polymerization product to obtain a plurality of fractions including a lubricating oil fraction and a recycle oil fraction of boiling range intermediate lubricating oil and gasoline, and recycling said recycle oil fraction to the initial distillation operation.

2. A method for producing a sulfur-free high grade lubricant from bituminous schists, which comprise initially distilling said schists in the presence of a recycle oil fraction of boiling range intermediate lubricating oil and gasoline and obtained from a prior fractional distillation operation, to produce a distillate oil, subjecting the distillate oil so produced to fractional distillation to obtain a lighter fraction and a heavier fraction, subjecting the lighter fraction to a polymerization treatment with a metal halide catalyst of the Friedel and Crafts type to produce a polymerization product, fractionating the polymerization product to obtain a plurality of fractions including a lubricating oil fraction and a recycle oil fraction of boiling range intermediate lubricating oil and gasoline, and recycling said recycle oil fraction together with the heavier fraction of the prior fractional distillation to the initial distillation operation.

3. A method for producing a sulfur-free high grade lubricant from bituminous schists, which comprises initially distilling said schists in the presence of a recycle oil fraction of boiling range intermediate lubricating oil and gasoline and obtained from a prior fractional distillation operation, to produce a distillate oil, subjecting the distillate oil so produced to fractional distillation to obtain a lighter fraction and a heavier fraction, subjecting the lighter fraction to a polymerization treatment with a metal halide catalyst of the Friedel and Crafts type to produce a polymerization product, fractionating the polymerization product to obtain a plurality of fractions including a lubricating oil fraction and a recycle oil fraction of boiling range intermediate lubricating oil and gasoline, and recovering and polymerizing the gasoline vapours and the easily condensable gases formed in the distillation of the schists.
4. A method for producing a sulfur-free high grade lubricant from bituminous schists, which comprises initially distilling said schists in the presence of a recycle oil fraction of boiling range intermediate lubricating oil and gasoline and obtaining from a prior fractional distillation operation, to produce a distillate oil, subjecting the distillate oil so produced to fractional distillation to obtain a lighter fraction and a heavier fraction, subjecting the lighter fraction under constant stirring at adjustable temperature to a polymerization treatment with a metal halide catalyst of the Friedel and Crafts type to produce a polymerization product, fractionating the polymerization product to obtain a plurality of fractions including a lubricating oil fraction and a recycle oil fraction of boiling range intermediate lubricating oil and gasoline, and recycling said recycle oil fraction to the initial distillation operation.
